UNITED STATES PATENT OFFICE

2,601,097

MASS SPECTROMETER FOR SIMULTANEOUS MULTIPLE GAS DETERMINATIONS

Arthur R. Crawford, Worthington, Ohio

Application July 20, 1949, Serial No. 105,808

2 Claims (Cl. 250—419)

10. *Classification of the new family*

1

This invention relates to improvements in mass spectrometers, having particular reference to a spectrometer especially designed for analyses of individual gases which comprise a body of mixed gases, whereby to disclose continuously variations in the relative abundance or concentration of such individual gases.

There exists at the present time a need for a continuously recording gas analyzer in the field of respiratory research, as an adjunct in diagnosing various lung disorders. It is, therefore, an object of the present invention to provide gas-analyzing apparatus for disclosing continuously by tracings on a motion picture film or the like the component gases present in the exhaled breath, including variations in concentration of the individual gases present when a given test is being conducted.

It is another object of the invention to provide a mass spectrometer so constructed as to form an instantaneously and continuously operating analyzer for effecting qualitative and quantitative determinations of the individual components present in a body of mixed gases.

In providing for the continuous analysis of the composition of human breath, a primary problem has been to minimize the time lag of the apparatus, that is, the interval of time occurring between an actual change in the concentration of an individual gas and the notation of such change on a registering or recording device therefor. In a breath analyzer, it is essential to render said time lag as small as possible, since the average human subject exhales and inhales once every six seconds. The usual mass spectrometer as heretofore constructed has a time lag of approximately twenty seconds or more in the interval occurring between the change in gas concentration and recordation of such change.

It is, therefore, a further object of the present invention to provide a mass spectrometer in which the element of time lag is reduced to a negligible degree.

A further object is to provide an analyzer capable of handling simultaneously the three main components of the breath, namely, carbon dioxide, nitrogen, and oxygen, so that such components may be recorded simultaneously, whereby changes in concentration of any one of the three gases can be seen with respect to the others at any given instant while a test is being conducted.

For a further understanding of the invention, reference is to be had to the following description and the accompanying drawings in which:

Fig. 1 is a schematic view of a mass spectrometer formed in accordance with the present invention;

Fig. 2 is an enlarged longitudinal sectional

view taken through the needle valve assembly of the apparatus;

Fig. 3 is an enlarged detail sectional view of the nozzle tip region of the valve on the line 3-3 of Fig. 2;

Fig. 4 is a similar view taken through the tip of the sample-introducing nozzle.

Referring more particularly to the drawings, there has been disclosed at 1 the needle valve assembly of my improved spectrometer. The gas sample to be analyzed is drawn into the valve through an open tube indicated at 2. This tube is inserted into a body member 4 so that the gas sample to be analyzed is drawn into a longitudinally extending passage 5 provided in said body member. At one end, the body member is formed with a collar 6 which engages with a gasket 1, the latter being arranged between the outer face of the collar 6 and an adjacent face of an orifice member 8.

20 The member 8 comprises a circular head plate 9 which is detachably secured to the upper end of a spectrometer tube T. The plate 9 is formed with an axial extension 10 which is externally threaded at its outer end for the reception of an internally threaded sleeve 11, the latter being formed with an inturned flange 12 which cooperates with the collar 6 of the body member 4 for the purpose of clamping said body member 30 to the orifice member.

The extension 10 terminates in a nozzle tip 13 having a tapered outer end 14, said tip being formed with a longitudinally extending axial passage 15 which communicates with a pair of larger longitudinally extending bores 16 provided in the extension 10, the bores 16 being in communication with the interior of the tube T. The extreme outer end of the tip, as shown in Fig. 4, is countersunk as at 17 to facilitate gas collection.

40 tion therein. The tip 13 is spaced from the walls
of the passage 5 provided in the body member 4,
so that the main body of the gas undergoing sam-
pling or testing may travel through the passage 5
without diversion and find exit through a pipe
45 line 18 leading to a suction-producing pump, not
shown.

50 Threaded, as at 19, on the outer end of the body member 4 is a thimble 20 which is formed axially and longitudinally with an internally threaded bore 21 for the reception of a needle-carrying thumb screw 22. The outer end of this screw is headed as at 23 and disposed beyond the thimble 20 where it is readily accessible for manual adjustment. The screw 22 carries a fine needle rod 24 which extends through an axial passage formed in the screw 22 and is held in connection therewith by one or more transverse set screws shown at 25, and which pass through the screw head 23. The rod 24 projects longitudinally and axially beyond the inner end of the

screw 22, passing through a rubber sealing disk 28 which is clamped between the thimble 20 and the adjoining end of the body member 4, the needle rod projecting into the passage 5, and thence to the small diametered axial passage 15 formed in the tapered outer end of the nozzle tip 13. With this apparatus, it is possible to change the rods or needles 24 to vary their diameters, without breaking the partial vacuum which exists within the apparatus.

The feathered or countersunk end 17 of the passage 15, aided by high gas velocities within the passage, serve to minimize back diffusion and to give satisfactory linear results. In addition, the time lag of the instrument by this construction is reduced to less than one hundredth (.01) part of a second. The gas samples handled by the apparatus are thus obtained while the subject is normally breathing through an ordinary rubber mouthpiece of the type shown at 27. The breath passing through the outlet passage 28 of the mouthpiece is introduced in part into a hypodermic needle 29, inserted through the walls of the rubber mouthpiece, the other end of the needle being connected with the tube 2. Thus breathing on the part of the patient is not restricted and excitement is avoided during the making of the test.

The gas samples which pass through the needle valve orifice enter a conventional ionizing head 30 arranged within the upper end of the tube T. Within the head 30, the gas is subjected, as usual, to electron bombardment. The ions formed by this bombardment find no field within the head but as they diffuse in the form of a beam through a small slit 30a in the bottom 30b of the head, they are subjected to an acceleration potential of about 1500 volts, collimated by slits in other plates 31 and projected through the vacuumized tube into a neck 32 which is surrounded by a permanent or electromagnet 33. In the magnetic field produced by the magnet 33, the ion beams emanating from the head 30 are resolved, the ionized particles of lighter weight or low mass being diverted by the magnetic field to a greater extent than those of heavier weight or greater mass so that the ions of the different gases of the mixture undergoing analysis are separately and individually deposited on the spaced collector plates indicated at 34, 35 and 36 after passing through restricted slits 36a. Each of the collector plates is connected in a conventional manner to the grid of an electrometer tube 37. The intensity of the ion currents falling upon the collector plates 34, 35 and 36 is measured by galvanometers, indicated at 38, arranged in the output circuits of a D. C. amplifier 39, the latter being connected in any conventional manner to the electronic tubes 37.

The electrons in the ionizing region of the head 30 may be obtained from an electrically heated tungsten filament shown at 40, accelerated across the tube, through the head and collected by a trap 41 on the other side of the head. The magnetic field in the neck 32 is preferably produced by a permanent magnet with 4000 gauss field strength. The ions collected are discharged by the electron current through high volume resistance provided in the amplifier 39.

The movable elements of the galvanometers 38 are provided with light reflectors so disposed that light beams discharged from the light source 42 incident upon the light reflectors of the galvanometers are diverted and directed upon a motion picture film strip 43 traveling in a camera unit 44.

Thus with the apparatus comprising the present invention, the three main components of the breath are recorded continuously and simultaneously, so that changes in concentration of any of the three can be determined with respect to the others so far as a given time base is concerned. Three identical amplifiers are employed with three collector systems and the output of each recorded by means of mirror-type galvanometers on a common film strip. The great advantage of such an instrument in any type of lung disorder is obvious. However, I do not limit the use of my apparatus to such a specific field but reserve the right to employ the same in all such fields to which it is adapted and of advantage.

I claim:

1. In apparatus for analyzing a mixture of gases; a mass spectrometer having an ionization chamber and a gas sample-receiving chamber;
- 20 a nozzle extending into said sample-receiving chamber and formed with a restricted passage communicating at one end with said ionization chamber and terminating at its opposite end in an outwardly flaring funnel-shaped inlet opening into said sample-receiving chamber; a valve stem arranged in longitudinal alignment with the inlet opening of said nozzle and movable to regulate the rate of flow of gas from said sample-receiving chamber to said ionization chamber; and means for establishing a positive flow of gas to be analyzed through said sample-receiving chamber and in and around said nozzle.
- 25 2. In a mass spectrometer; a casing structure including a head and an internal ionization chamber; a nozzle extending from said head and formed with a fine axially and longitudinally disposed gas passage terminating at the outer end of said nozzle in an enlarged funnel-shaped inlet opening and communicating at its opposite end with said ionization chamber; a separate casing member connected with said head in coaxial relation to said nozzle, said separate casing member being formed with an internal sample-receiving chamber into which the nozzle of said head projects;
- 30 35 a threaded member carried by said separate casing member; a longitudinally extending needle valve joined with said threaded member, said valve being movable axially of the fine passage of said nozzle upon adjustment of said threaded member to control the flow of gas from the sample-receiving chamber of said separate casing member through the fine passage of said nozzle and into the ionization chamber of said spectrometer; and means for effecting a forced passage
- 35 40 45 50 55 60 of gas to be tested by the spectrometer through said sample-receiving chamber in a direction so that a portion of the total quantity of the gas introduced into said sample-receiving chamber may be directed through the inlet opening of said nozzle and into said ionization chamber.

ARTHUR R. CRAWFORD.
